BRIEF CASE

Simon B. Reuben, Chicago, Ill.

Application May 2, 1940, Serial No. 333,010

2 Claims. (Cl. 281—19)

The invention relates to brief cases, and more particularly to brief cases which are equipped with loose leaf binders and used as portfolios.

It is often desirable to convert a portfolio 5 into a brief case, especially where a large number of files or books are to be carried.

It, therefore, constitutes one of the objects of the invention to provide a portfolio with a removable binder to enable conversion to an ordinary brief case.

A further object aims at providing a removable binder with the securing means permanently attached to the binder.

A still further object constitutes the provision 15 of a portfolio which, after the elimination of the binder, leaves the inside smooth and neat in appearance.

It is a still further object to releasably secure the binder in such manner that, upon removal 20 of the binder from the portfolio, only two small holes are visible in the inside, so that the portfolio substantially has the appearance of an ordinary brief case. No holes are visible on the outside thereof.

With these and other important objects in view, the invention comprises the means described in the following specification, particularly pointed out in the claims forming a part thereof, and illustrated in the accompanying 30 drawing, in which:

Fig. 1 is a top plan view of an opened portfolio constructed in accordance with my invention.

Fig. 2 is an enlarged section on the line 2—2

35 of Fig. 1.
Fig. 3 is a fragmentary top plan view of the back of the portfolio with the binding mechanism removed, and

Fig. 4 is a perspective view of a retaining bar 40 to which the binding mechanism is secured.

Referring to the several views in the drawing, the portfolio comprises a front cover 18 and a rear cover 16 connected by an integral back 12.

As is well known, the edges of the cover are 45 folded over and a strip of cloth 13 is secured by a seam 14 thereto. A slide fastener 15 is secured to

the inner edge of the strip 13 and is actuated by a handle 15' when the covers are brought together to close the portfolio.

The binder mechanism, which per se does not form a part of the invention, includes a casing 5 16, sectionalized rings 17 and a bar 18 in the casing. The covers and back have an inner lining 19.

Between the lining 19 and the back a longitudinal bar 20 is interposed, which has bosses 21. 10 The bosses are provided with threaded bores. The bosses extend through apertures 22 in the lining.

As shown in Fig. 2, a screw 23 is permanently attached to the binding by having its shank 24 15 provided with a circumferential groove 25 in to which the edge of an aperture 26 extends. The lower reduced end 27 is threaded and is adapted to be screwed home into the bosses.

It is obvious that the binding mechanism 20 may be removed by loosening the screws 23 and, after such removal, nothing is visible but the upper end of the bosses 21, so that a neat appearance is afforded on the inside of the portfolio even though the binding mechanism is removed. 25

While the drawing shows one embodiment of the invention, various changes and alterations may be made without departing from the spirit of the invention. All such changes and alterations are included, which constitute departures within the scope of the invention, as defined in the appended claims. 30

I claim:

1. In a portfolio having a back, a binding mechanism, apertured bosses in the back of the portfolio and terminating flush therewith, and screws permanently attached to said binding mechanism and adapted to enter said bosses. 35

2. In a portfolio having a back, a bar concealed within the back of the portfolio and provided with one or more bosses substantially flush with the top surface of the back, a binding mechanism, and screws removably securing said binding mechanism to said bosses. 40 45

SIMON B. REUBEN.
